WINDOW VENTILATOR

Frederick Lemmer, Irvington, N. J.

Application July 27, 1940, Serial No. 347,981

11 Claims. (Cl. 296—84)

The present invention relates to new and useful improvements in ventilators for windows and has for its primary object to provide a device of this character designed particularly for use in the windows of automobiles and other vehicles.

A further important object of the present invention is to provide a window ventilator of this character adapted for removably positioning in the window frame and embodying a pair of ventilating wings projecting at diametrically opposite sides from the pivotal mounting of the ventilator and adapted for movement into the desired adjusted position for controlling the admission of air into the window.

Another object is to provide a device of this character of simple and practical construction, which is efficient and reliable in performance, relatively inexpensive to manufacture, that may be easily and quickly installed in operative position in the window frame without necessitating any fastening means therefor and which at the same time is inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a view in elevation of the ventilator shown in position in the window frame, the upper and lower portions of the frame being shown in section.

Figure 2 is a transverse sectional view taken substantially on the line 2—2 of Figure 1.

Figure 3 is a vertical sectional view through the adjustable clamping support for the ventilator.

Figure 4 is a plan view of one of the blanks forming one of the wings of the ventilator,

Figure 5 is a transverse sectional view taken substantially on the line 5—5 of Figure 3,

Figure 6 is an edge elevational view of the wing frame, and

Figure 7 is a plan view of the cross-head for the top of the clamping support.

Referring now to the drawings in detail wherein for the purpose of illustration I have disclosed a preferred embodiment of the invention, the numerals 5 and 6 designate a pair of duplicate wing frames, each of the frames preferably being stamped from sheet metal as shown in Figures 4 and 6 of the drawings, and including a substantially rectangular frame member 7 having each end portion formed with outwardly project-

ing tabs 8 and one longitudinal edge portion likewise formed with outwardly projecting tabs 9, the tabs being adapted to be bent along the dotted lines shown at 10, for folding upon the frame for securing the glass panel 11 in position in the frame.

The other longitudinal edge of the frame 7 is formed with a longitudinally extending channel 12 having a flange 13 on the outer edge thereof, 10 the channel 12 of the pair of frames being adapted to form a tubular center post 14, the flange 13 and the edge of the frame at the side of the channel portion 12 opposite from said flange being provided with openings 15 adapted to receive rivets or the like 16 for securing the frames in flatwise engagement with the respective frames 7 projecting diametrically opposite from the tubular member 14.

Inserted upwardly in the bottom end of the 20 tubular member 14 is a headed stud 17 rising from a plate 18, the lower end of the tubular member 14 being bent inwardly as shown at 19 to prevent removal of the head therefrom. The plate 18 is formed adjacent its outer edge with an upstanding annular rib 20 adapted to reinforce the edge portion of said plate, the rib having spaced openings 21 formed therein. Secured to the under side of the plate is a resilient 25 pad 22, preferably constructed of rubber and adapted to bear against the bottom of the window frame 23.

The lower edges of the pair of frames or wings 7 are adapted to enter the openings or notches 21 to secure the wings in rotatably adjusted position in the window frame.

35 The intermediate portion of the tubular member 14 is provided with a pair of inwardly struck lugs 24 forming a support for an expansible coil spring 25 which is positioned in said tubular member, the upper edge of said spring bearing against an adjusting nut 26 threaded on a stem 27 positioned in the tubular member and projecting upwardly from the upper end thereof.

The nut 26 is provided with wings 28 projecting from diametrically opposite sides thereof and 40 slidably positioned in slotted openings 29 formed in the tubular member 14.

The upper end of the screw 27 is formed with a cross-head 30 on which is suitably secured a rubber pad 31 adapted for bearing against the upper portion of the window frame as shown at 50 32. The cross-head is formed with an opening 33 adapted to receive the reduced upper end 34 and the screw 27, the end 34 having a loose fit in the opening and upset to permit sufficient tilting of the head in accordance with any in-

clination occurring in the upper window frame 32.

Also as shown to advantage in Figure 2 of the drawings, the flanges 13 of each frame member 7 are engaged by the upper and lower tabs 8 of the adjacent wing frame to assist in securing the pair of frames rigidly together.

From the foregoing it will be apparent that the cross-head 30 at the top of the ventilator serves as an adjustable clamping member for clamping the device in position between the upper and lower edges of the window frame, the nut 26 providing for the proper adjustment of the clamping member and the spring 25 yieldably maintaining the device in position.

It is believed the details of construction, operation and advantages of the device will be readily understood from the foregoing without further detailed explanation.

Having thus described the invention, what I claim is:

1. A window ventilator of the class described comprising a pair of duplicate ventilator frame members including vertical and horizontal frame portions, means for securing a glass panel in each of said frame members, means for connecting one of the vertical edges of each of said frame members together to form a post, and means for adjustably mounting said post in position in a window opening.

2. A window ventilator of the class described comprising a pair of duplicate ventilator frame members including vertical and horizontal frame portions, means for securing a glass panel in each of said frame members, means for connecting one of the vertical edges of each of said frame members together to form a post, a base secured to the bottom of the post and an adjustable clamping member projecting upwardly from the upper edges of the post and cooperating with said base for removably securing the assembled frames in position in a window opening.

3. A window ventilator of the class described comprising a pair of duplicate ventilator frame members, means for securing a glass panel in each of said frame members, means for connecting one edge of said frame members together, a base secured to the bottom of the connected edge of said frame members and a spring projected clamping member extending upwardly from the upper connected edges of said frame members for removably securing the assembled frame in position in a window opening.

4. A window ventilator comprising a pair of duplicate ventilator frame members of substantially rectangular form, the long edges of the frame being disposed vertically, bendable tabs formed on the upper and lower edges of each of the frame members and also along one of the longitudinal edges of said frame members and adapted for bending over the edges of a glass panel for securing the same in position in said frame members, the other of said longitudinal edges of each frame member being provided with a vertically extending channel, means for securing the channels of each of the frame members in opposed relation to form a tubular center post with the wings projecting horizontally from diametrically opposite sides of said post and means at the upper and lower ends of said post for removably securing the same in position in a window opening.

5. A window ventilator comprising a pair of duplicate ventilator frame members of substan-

tially rectangular form, the long edges of the frame being disposed vertically, bendable tabs formed on the upper and lower edges of each of the frame members and also along one of the longitudinal edges of said frame members and adapted for bending over the edges of a glass panel for securing the same in position in said frame members, the other of said longitudinal edges of each frame member being provided with a vertically extending channel, means for securing the channels of each of the frame members in opposed relation to form a tubular center post with the wings projecting horizontally from diametrically opposite sides of said post, a base at the lower end of said post having an upstanding stud rotatably inserted in the post, a screw projecting upwardly through the top of the post, adjusting means for said screw, spring means yieldably projecting the screw outwardly of the post and a clamping head on the outer end of said screw and cooperating with the base for removably securing the post in position in a window opening.

6. A ventilator of the class described comprising a pair of frames adapted for mounting panels therein, one edge of each frame being connected to form a post structure, said frames projecting from diametrically opposite sides of the post, a base and a head at opposite ends of the post adapted for rotation relative to the post and providing means for clamping the post in a window opening, and a circular upstanding rib on the base having notches adapted to receive the lower edges of said frames for securing the frames in rotatably adjusted position.

7. A ventilator of the class described comprising a pair of frames adapted for mounting panels therein, one edge of each frame being connected to form a post structure, said frames projecting from diametrically opposite sides of the post, a base rotatably supporting the lower end of the post and having means limiting upward movement of the post on the base, a spring projected head at the upper end of the post and cooperating with the base to clamp the post and frames in a window opening, and a circular rib on the base having notches adapted to receive the lower edges of the frames for securing the frames in rotatably adjusted position.

8. A window ventilator of the class described comprising a pair of duplicate ventilator frame members including vertical and horizontal frame portions, means for securing a glass panel in each of said frame members, means for connecting one of the vertical edges of each of said frame members together to form a post, a base rotatably secured to the bottom of the post and an adjustable clamping member projecting upwardly from the upper edges of the post and having a head rotatably mounted on its upper end, said head cooperating with said base for removably securing the assembled frames in position in a window opening and providing for the horizontal swinging adjustment of the said frame members.

9. A window ventilator of the class described comprising a pair of duplicate ventilator frame members, means for securing a glass panel in each of said frame members, means for connecting one edge of said frame members together, a base rotatably secured to the bottom of the connected edge of said frame members and a spring projected clamping member extending upwardly from the upper connected edges of said frame members for removably securing the assembled

frame in position in a window opening, said clamping member having a clamping head rotatably mounted thereon.

10. A window ventilator comprising a pair of duplicate ventilator frame members of substantially rectangular form, the long edges of the frame being disposed vertically, bendable tabs formed on the upper and lower edges of each of the frame members and also along one of the longitudinal edges of said frame members and adapted for bending over the edges of a glass panel for securing the same in position in said frame members, the other of said longitudinal edges of each frame member being provided with a vertically extending channel, means for securing the channels of each of the frame members in opposed relation to form a tubular center post with the wings projecting horizontally from diametrically opposite sides of said post and means at the upper and lower ends of said post for removably and rotatably securing the same in position in a window opening.

11. A window ventilator comprising a pair of duplicate ventilator frame members of substan-

tially rectangular form, the long edges of the frame being disposed vertically, bendable tabs formed on the upper and lower edges of each of the frame members and also along one of the 5 longitudinal edges of said frame members and adapted for bending over the edges of a glass panel for securing the same in position in said frame members, the other of said longitudinal edges of each frame member being provided with a vertically extending channel, means for securing the channels of each of the frame members in opposed relation to form a tubular center post with the wings projecting horizontally from diametrically opposite sides of said post, a base at the lower end of said post having an upstanding stud rotatably inserted in the post, a screw projecting upwardly through the top of the post, adjusting means for said screw, spring means yieldably projecting the screw outwardly of the post and a clamping head rotatably mounted on the outer end of said screw and cooperating with the base for removably securing the post in position in a window opening.

FREDERICK LEMMER.
